UNITED STATES PATENT OFFICE.

WILLIAM L. BLISS, OF NIAGARA FALLS, NEW YORK, ASSIGNOR TO THE UNITED STATES LIGHT & HEATING COMPANY, OF NEW YORK, N. Y., A CORPORATION OF MAINE.

RESISTANCE UNIT.

1,073,320.

Specification of Letters Patent. Patented Sept. 16, 1913.

Application filed January 6, 1911. Serial No. 601,084.

To all whom it may concern:

Be it known that I, WILLIAM L. BLISS, a citizen of the United States, residing at Niagara Falls, in the county of Niagara and State of New York, have invented new and useful Improvements in Resistance Units, of which the following is a full, clear, concise, and exact description, reference being had to the accompanying drawing, forming 5 a part of this specification.

My invention relates to resistance units and to terminal connections therefor.

One of the objects of the invention is to provide simple and effective means whereby 15 a resistance unit may be readily connected in circuit and disconnected therefrom simply by forcing it or snapping it into resilient terminal clips or forcibly withdrawing it therefrom.

20 In the accompanying drawings I have illustrated one of a number of possible, simple and practical embodiments of my invention.

Figure 1 is a side elevation of this embodiment partly in section. Fig. 2 is an end view of the device. Fig. 3 is a perspective view, showing the parts in the order in which they are assembled.

The resistance element itself forms no 25 part of my present invention and may be of any approved type. It is preferably mounted on a spool of porcelain or other insulating material whose ends 1 appear in the drawings, and is incased in a metal 30 jacket or casing 2 carried by said spool, said jacket being secured by bands 3 of any suitable type.

The terminal members proper comprise 40 cup-shaped ferrules 4 of any suitable conducting material such as brass, which ferrules are secured to the opposite ends of the spool by means of a bolt 5 and a nut 6. The bolt passes entirely through the spool and is held out of contact with the terminal members by insulating bushings 7 of fiber or other suitable material, and by washers 8 also preferably of fiber. Of course I do not limit myself to these details, as any suitable means for supporting said ferrules in 45 proper relation to the main body of the device, may be employed, whether said body is of insulating material or not.

Each terminal member 4 is provided with a hole 9 adapted to receive the bared end 55 of conductor 10, which bared end is sol-

dered to the terminal. These conductors pass through an opening in the bosses 11 on the spool and connect with the resistance unit, not shown. The recesses in the cup-shaped members are preferably packed with 60 insulating cement or other suitable non-conducting material 12, whereby accidental contact with and mechanical derangement of the inclosed parts is prevented.

The terminal contact ferrules are adapted 65 to snap into a resilient clip member 13 which may be of any suitable form, such for example, as that shown in Fig. 2, although I do not limit myself to this construction.

It is obvious that any one of a number of 70 suitable forms of contact member and co-operating terminal clip may be employed as long as the resulting construction permits the device to be readily grasped and forced into position in contact with the terminal 75 clips and to be readily removed therefrom. It will be apparent, therefore, that the invention is not limited to the details of construction shown and described, but includes 80 any suitable equivalent means for accomplishing the same desired result.

What I claim as new and desire to secure by Letters Patent of the United States, is:—

1. A resistance unit comprising a resistance element, a surrounding casing, terminal members adjacent each end of said casing, and means electrically insulated from 85 said terminal members mechanically securing said parts together to form a unitary structure.

2. A resistance unit comprising a resistance element, a support therefor, cup-shaped terminal members for said resistance, a bolt passing through said members and said support for securing said members thereto, and means insulating said bolt from said terminal members.

3. A resistance unit comprising a resistance element, a support therefor, cup-shaped contact ferrules electrically connected to 100 said resistance unit, and means passing through said ferrules and said support for securing said ferrules to said support, said means being insulated from said ferrules.

4. In combination, a resistance element, an insulating support therefor having projections thereon, electrical connections for said resistance element passing through openings in said projections, contact terminal members to which said electrical con- 105

nections are secured, said contact members comprising conducting cup-shaped members secured to said support by a bolt, and an insulating bushing and insulating washer between said bolt and each of said contact members.

5. In combination, a body of insulating material, a resistance wire carried thereby, aligned terminal members on opposite ends of said body, each member consisting of a cup-shaped conductor having a central hole in the base and a radial aperture in the cylindrical wall, a bolt passing through the central hole in each terminal member, an insulating bushing surrounding the bolt at each of said holes and insulating washers secured against the bottom of each of said cup-shaped members by said bolt whereby the various parts are maintained in assembled relation, each end of said resistance wire passing through one of said radial apertures and soldered within to the corresponding terminal member.

6. In combination with a pair of supporting clips, a resistance unit, said unit comprising a resistance element provided with terminals coöperating with said clips, and a casing surrounding said resistance element, but insulated therefrom and from said terminals.

7. In combination with a pair of supporting clips, a resistance unit, said unit comprising a resistance element provided with terminals coöperating with said clips, a casing surrounding said resistance element, but insulated therefrom and from said terminals, and insulated means mechanically uniting said terminals and casing to form a unitary structure.

In witness whereof, I have hereunto subscribed my name in the presence of two witnesses.

WILLIAM L. BLISS.
